UNITED STATES PATENT OFFICE

SIDNEY D. LIGHT, OF DETROIT, MICHIGAN

LOOSE LEAF SUPPORTING ARRANGEMENT

Application filed December 23, 1929. Serial No. 415,931.

This invention relates to improvements in loose leaf supporting arrangements, and refers more particularly to loose leaf binders wherein parallel tongues are provided substantially centrally of their width which usually extend the full height of the binder and between which leaves are to be held.

It is an object of the invention to provide a loose leaf supporting arrangement wherein binding posts having annular grooves adjacent their outer extremities extend laterally from one of the tongues and are adapted to project through apertures in the other tongue, and wherein pivotal locking members on the said other tongue hold the binding posts relative to the latter so that leaves through which the posts pass are held between the tongues.

Other objects of the invention are to provide such a loose leaf supporting arrangement, wherein the pivotal locking members are so constructed that they reinforce adjacent portions of the tongue on which they are mounted and through which the binding posts pass, and wherein the various parts are simple to manufacture, assemble and use.

With these and other objects and advantages in view which will become apparent as the specification proceeds, the invention is hereinafter more fully described with the aid of the accompanying drawings, in which:

Figure 1 illustrates a perspective view of a loose leaf binder equipped with the invention.

Figure 2 is an enlarged plan view of a portion of a binder showing the leaf-supporting arrangement.

Figure 3 is an enlarged side view of the supporting arrangement without a binder, and

Figure 4 shows an enlarged cross-sectional view of a portion of a binder with leaves therein and the supporting arrangement; the latter being shown as a section on the line 4-4 of Figure 3.

Referring to the drawings, 1 designates a conventional binder having two parallel tongues 2 and 3 positioned substantially centrally thereof and extending inwardly for the full height of the binder. Between these

tongues leaves 4 are held. Secured to the tongue 2 are a plurality of binding posts 5 which project towards the tongue 3 and are adapted to pass through apertures 6 in the latter. The posts 5 have annular grooves 7 formed around them adjacent their outer extremities.

The binding posts 5 may be of any desired construction and may be secured to the tongue 2 in any desired manner. In the present instance they consist of tubular internally threaded members 8 which extend through openings formed in the tongue 2 and have integral flanges 10 intermediately of their length which bear against the inner side of the tongue 2. These members 8 are held in position by their expanded ends 8a which bear against washers 11 placed around their ends. These washers 11 rest also against the outer side of the tongue 2. In threaded engagement with the members 8 are extensions 12 around which the annular grooves 7 are formed adjacent their outer extremities. These extensions may of course be adjusted so that their grooves 7 are positioned at various distances from the tongue 2 to adjust the spacing between the tongues 2 and 3 to suit the number of leaves 4 held between them.

Locking members 14, substantially U-shaped in cross-section, are pivotally mounted on the tongue 3 adjacent the apertures 6 by rivets 15. These locking members are so constructed and arranged that their folded intermediate portions 14a may lie adjacent portions of the outer margin of the tongue 3 and parallel with the latter. In the sides of the members 14 opposed marginal recesses 16 and 16a are formed. The recesses 16 are of such size that their margins may engage the binding posts grooves 7 and hold them against axial movement; these recesses are formed in the outer sides of the members 14. The recesses 16a formed in the inner sides of the members 14 are larger than the recesses 16 so that when the latter engage the grooves 7, the recesses 16a partly encircle but lie clear of the binding posts 5.

At the pivoted ends of the members 14 their intermediate folded portions are cut away as shown at 14b so as to permit the mem-

- bers to be turned from their downturned position shown at A in Figure 1 into the upturned position shown at B. In order to facilitate the turning of the members 14, their outer sides are cut away as shown at 17 at their ends remote from the rivets 15, so that finger holds are afforded which lie substantially parallel with their intermediate folded portions 14a and adjacent thereto.
- 10 The operation of the device is, of course, as follows: When it is desired to open the leaf-supporting arrangement the members 14 are moved pivotally from their position shown at A to that shown at B when the binding posts 6 are free to be withdrawn from the apertures through the tongue 3. The leaves 4 are then free to be removed from the binding posts.
- From the foregoing it will be clearly seen that I have not only devised a simple and efficient method of supporting leaves in binders and of holding binding posts against movement relative to a tongue through apertures in which the said posts are intended to remain, but that the tongue adjacent its apertures is strengthened by the locking members, and also that on account of the sides of the said members lying adjacent both sides of the tongue on which they are pivotally mounted the possibility of the members becoming accidentally disengaged from the binding posts grooves is materially reduced.
- While the preferred construction of the invention has been described and shown, it is understood that alterations and modifications may be made thereto provided the said alterations and modifications fall within the scope of the appended claims.
- What I claim as my invention and desire to secure by Letters Patent is:
- 40 1. In an arrangement of the character described, the combination of a binder cover having two opposed and parallel tongues between which leaves are to be mounted, binding posts secured to one tongue and extending laterally therefrom, the other tongue having apertures therethrough through which the binding posts may pass, said posts having annular grooves formed around them, and locking members pivoted on said other tongue, said members being folded so as to be substantially U-shaped in section so that their intermediate folded portions extend over the outer margin of said other tongue and their sides are disposed on opposite sides of said other tongue, said members having marginal recesses formed therein so that the sides of the latter may engage said annular grooves and hold the binding posts against movement.
- 45 2. In an arrangement of the character described, the combination of a binder cover having two opposed and parallel tongues between which leaves are to be mounted, binding posts secured to one tongue and extending laterally therefrom, the other tongue having apertures therethrough through which the binding posts may pass, said posts having annular grooves formed around them, and locking members pivoted on said other tongue, said members being folded so as to be substantially U-shaped in section so that their intermediate folded portions extend over the outer margin of said other tongue and their sides are disposed on opposite sides of said other tongue, said members having marginal recesses formed therein so that the sides of the latter may engage said annular grooves and hold the binding posts against movement.
- 50 3. In an arrangement of the character described, the combination of a binder cover having two opposed and parallel tongues between which leaves are to be mounted, binding posts secured to one tongue and extending laterally therefrom, the other tongue having apertures therethrough through which the binding posts may pass, said posts having annular grooves formed around them, and locking members pivoted on said other tongue, said members being folded so as to be substantially U-shaped in section so that their intermediate folded portions extend over the outer margin of said other tongue and their sides are disposed on opposite sides of said other tongue, said members having marginal recesses formed therein so that the sides of the latter may engage said annular grooves and hold the binding posts against movement.
- 55 4. In an arrangement of the character described, the combination of a binder cover having two opposed and parallel tongues between which leaves are to be mounted, binding posts secured to one tongue and extending laterally therefrom, the other tongue having apertures therethrough through which the binding posts may pass, said posts having annular grooves formed around them, and locking members pivoted on said other tongue, said members being folded so as to be substantially U-shaped in section so that their intermediate folded portions extend over the outer margin of said other tongue and their sides are disposed on opposite sides of said other tongue, said members having marginal recesses formed therein so that the sides of the latter may engage said annular grooves and hold the binding posts against movement.
- 60 5. In an arrangement of the character described, the combination of a binder cover having two opposed and parallel tongues between which leaves are to be mounted, binding posts secured to one tongue and extending laterally therefrom, the other tongue having apertures therethrough through which the binding posts may pass, said posts having annular grooves formed around them, and locking members pivoted on said other tongue, said members being folded so as to be substantially U-shaped in section so that their intermediate folded portions extend over the outer margin of said other tongue and their sides are disposed on opposite sides of said other tongue, said members having marginal recesses formed therein so that the sides of the latter may engage said annular grooves and hold the binding posts against movement.
- 65 6. In an arrangement of the character described, the combination of a binder cover having two opposed and parallel tongues between which leaves are to be mounted, binding posts secured to one tongue and extending laterally therefrom, the other tongue having apertures therethrough through which the binding posts may pass, said posts having annular grooves formed around them, and locking members pivoted on said other tongue, said members being folded so as to be substantially U-shaped in section so that their intermediate folded portions extend over the outer margin of said other tongue and their sides are disposed on opposite sides of said other tongue, said members having marginal recesses formed therein so that the sides of the latter may engage said annular grooves and hold the binding posts against movement.

70 apertures therethrough through which the binding posts may extend, said posts having annular grooves formed around them, and locking members pivotally mounted on said other tongue, said members being folded so as to be substantially U-shaped in section so that their intermediate folded portions extend over the outer margin of said other tongue and the sides of each member are disposed on opposite sides of said other tongue, 75 the sides of said members having marginal recesses formed therein to engage said annular grooves and the intermediate folded member portions terminating adjacent the pivoted ends of the members so that the latter may be turned relative to said other tongue for the sides of the recesses to be moved free of the annular grooves in the binding posts.
